(57) **CLAIM**

The ornamental design for a portable computer shaped learning machine, as shown and described.

DESCRIPTION

FIG. 1 is a front perspective view of the portable computer shaped learning machine showing my new design;
FIG. 2 is a front view of the portable computer shaped learning machine of FIG. 1;
FIG. 3 is a top plan view of the portable computer shaped learning machine of FIG. 1;
FIG. 4 is a left side view of the portable computer shaped learning machine of FIG. 1;
FIG. 5 is a right side view of the portable computer shaped learning machine of FIG. 1;
FIG. 6 is a rear view of the portable computer shaped learning machine of FIG. 1;
FIG. 7 is a bottom plan view of the portable computer shaped learning machine of FIG. 1; and,
FIG. 8 is a front perspective view of the portable computer shaped learning machine of FIG. 1 viewed in an opened position.
